United States Patent

Des. 237,939

Patented Dec. 9, 1975

237,939

VALVE CORE EXTRACTION TOOL

Ezekiel Seminario, 15500 Tustin Village Way,
Tustin, Calif. 92680

Filed Feb. 1, 1974, Ser. No. 438,556

Term of patent 14 years

Int. Cl. D8—05

U.S. Cl. D8—59

FIG.1

FIG.2

FIG.3

FIG.4

FIG.5

FIG.6

FIG. 1 is a pictorial view of my new valve core extraction tool;

FIG. 2 is a top plan view thereof;

FIG. 3 is a view in end elevation thereof;

FIG. 4 is a view in front elevation thereof;

FIG. 5 is a view in elevation of the other side thereof; and

FIG. 6 is a bottom plan view thereof.

I claim:

The ornamental design for a valve core extraction tool, as shown.
